UNITED STATES PATENT OFFICE

MARK ANTHONY, OF CLEVELAND, OHIO

PENCIL SHARPENER

Application filed April 23, 1928. Serial No. 272,021.

To the end of providing a pencil sharpener which may be easily and readily made, this invention is primarily directed. My novel idea is to fashion from a blank of metal by any appropriate metal working process, such as stamping, a piece of metal having configuration of such character that when it is rolled up or put in cylindrical form, it will have assumed all the requisite characteristics of the sharpener or pointer.

While the method of manufacturing the pencil pointers is one of the principal features of this invention, this method, because of its simplicity and ease of carrying out, has enabled me to include in the construction of a sharpener, several salient points of novelty from which highly beneficial results are derived when the device is used. By designing the extremities of the cutting edges so that they recede or assume an angular relation with respect to the remainder of the cutting blade, liability of the breaking of the lead point or the wood at the end of the cut portion thereof, is practically obviated.

For the efficient operation of a pencil sharpener, it is essential that a pencil be sharpened without necessitating a prolonged operation to give the desired results, and it is therefore highly desirable to have the main cutting edges extend longitudinally of a pencil on which it is to operate. Such a condition ordinarily would cause unsatisfactory results because the lead point is constantly broken and the wood marred and frayed. However, I have overcome the disadvantages accompanying the arrangement of the cutting edges, which permits of the most efficient operation of a pencil sharpener device, by causing the extremities to become inclined with the remainder of the said cutting edges.

The present invention comprehends the use of a casing or carrier for the sharpener, this casing having a double function in that it constitutes a support or carrier for the eraser.

A detailed object of the invention is to provide means for determining the condition of a pencil being operated on by the sharpener. In achieving this object, the casing is provided with keyhole slots in substantial

alignment with the cutting edges of the sharpening device proper so that the same is rendered visible during all stages of operation.

The invention includes further and more detailed objects and advantages as will in part become apparent and in part be herein-after stated.

For a full and more complete understanding of the invention, reference may be had to the following description and accompanying drawings, in which—

Fig. 1 is a perspective view showing a form of casing in which the novel sharpening device is received.

Fig. 2 is a side elevation of the sharpening device itself, which is adapted for insertion in the casing of Fig. 1.

Fig. 3 is a longitudinal section through the casing, showing the sharpener, in elevation, inserted therein.

Fig. 4 is a detailed view in perspective of an eraser adapted to cooperate with the casing and sharpener.

While only a preferred, specific embodiment of the invention is herein set forth, it is to be understood that I am not to be limited to the exact constructions illustrated and described, because various modifications of these details may be provided in putting the invention into practice within the purview of the appended claims.

In making a pencil sharpener in accordance with this invention, a blank of suitable metal is first fashioned to the desired shape by any approved process such as stamping. After the blank is shaped, it is put into cylindrical condition by the preferred process, such as rolling or deforming the metal, thereby forming a pair of mating edges which may be welded together; or if the blank be made from soft iron, as is desirable, the rolled blank may be tempered to cause it to retain the rolled condition.

The finished sharpener comprises a cylindrical portion 1 and a conical portion 2. The conical portion 2 is provided with recesses or slots 3, each having one side properly disposed to constitute a cutting edge 4. By referring particularly to Figures 1 and 2,

- it will be noted that the cutting edge 4 recedes at the point to provide a cutting edge inclined with respect to the remainder thereof as shown at 5. This same thought is carried out at the other extremity of the edges as shown at 6 but the inclination is in a somewhat opposite direction. That is, at 6 the inclined blade precedes the main cutting blade while at 5 it follows it, speaking relative to operation of the sharpening device. Needless to say, the recesses 3 permit of the removal and dispensing of cut portions of the pencil. The completed sharpener is indicated at D.
- 15 A main casing of any suitable metal referred to generally as E, comprises a cylindrical portion 8, a frusto-pyramidal portion 9, and a rectangular portion 10. The portion 10 is designed to receive and hold an eraser shown in Figure 4 and given the reference character 11.
- The cylindrical portion 8 terminates in an in-turned flange 12 that functions as a support and retainer for the sharpening device.
- 25 D when the various parts are completely assembled as shown in Figure 3. Slots 13 of keyhole formation are provided in the casing E at opposite points and extend throughout the length of the portion 9 and partly into the cylindrical portion 8 and rectangular portion 10. These slots are substantially aligned with the recesses 3 in the sharpening device D so as to render the said recesses visible. For the purpose of holding the various parts of the finished sharpener in their assembled relation, I prefer to avail of some metal having properties of resiliency so that the inherent resiliency of the metal of the casing will cause the eraser and sharpening device
- 30 40 D to remain in their proper positions.
- Having thus described my invention, what I claim as new and desire to secure by Letters Patent in the United States, is:
1. A pencil sharpener of the class described, comprising, in combination, a casing having slots therein, a sharpening device positioned interiorly of the casing and secured in position therein, the said sharpening device having slots therein in substantial alignment
  - 45 50 55 60 65 70 75 80 85 90 95 100 105 110 115 120 125 130
- with the slots in the casing to render visible at all times a pencil being sharpened, the sharpening device being provided with main cutting edges extending longitudinally of the pencil being sharpened, the extremities of the cutting edges being angularly inclined with respect to the remainder of the cutting edges to prevent breaking of the point of the pencil.
2. A combination pencil sharpener and eraser holder of the class described, comprising a casing having a cylindrical portion, and an enlarged rectangular socket portion constituting a socket for an eraser, a tapered portion intermediate the cylindrical and rectangular portions, the said tapered portion

having keyhole slots therein, a sharpener positioned within the casing and secured in position therein, the sharpening device having a tapering part projecting into the tapered portion of the casing and having slots in substantial alignment with the slots in the casing to render visible at all times a pencil being operated upon by the sharpener and forming means of egress for pencil shavings, the sharpener also having main cutting edges extending longitudinally of the pencil being pointed, the extremities of the cutting edges being angularly inclined with respect to the remainder of the cutting edges.

3. A combination pencil sharpener and eraser holder of the class described, comprising a casing having a cylindrical portion, a frusto-pyramidal portion merging into the cylindrical portion, a rectangularly shaped socket portion united with the pyramidal portion, the pyramidal portion having oppositely disposed slots therein, a sharpener within the casing and secured in position within the cylindrical portion and having a regularly tapered part projecting into the pyramidal portion of the casing, the point of the sharpening device being positioned adjacent the broad base of the pyramidal portion of the casing, the sharpener having slots in substantial alignment with the slots in the casing to render visible at all times a pencil being pointed by the sharpener and forming means of egress for pencil shavings, the sharpener being provided with main cutting edges extending longitudinally of the pencil being pointed, the extremities of the cutting edges being angularly inclined with respect to the remainder of the cutting edges.

In testimony whereof I affix my signature.

MARK ANTHONY. 105
